G. NEILSON.
VENTILATING RAILWAY CARRIAGES.

No. 10,449.

Patented Jan. 24, 1854.

UNITED STATES PATENT OFFICE.

GEO. NEILSON, OF BOSTON, MASSACHUSETTS.

VENTILATING RAILROAD-CARS.

Specification of Letters Patent No. 10,449, dated January 24, 1854.

To all whom it may concern:

Be it known that I, GEORGE NEILSON, of Boston, in the county of Suffolk and State of Massachusetts, have invented certain new and useful Improvements in Ventilating Railway-Carriages; and I do hereby declare that the same is fully described and represented in the following specification and the accompanying drawings, letters, figures, and references thereof.

10 Of the said drawings, Figure 1 denotes a side elevation of a railway carriage body having my improvements applied to it. Fig. 2, is a longitudinal, vertical and central section of it. Fig. 3, is a horizontal section taken through the middle of the windows. Fig. 4 is a central, vertical and transverse section. Fig. 5, is a horizontal section of the air induction apparatus, the said section being taken through its receiving mouths and the capillary partitions, to be herein-after described.

15 In the said drawings, A exhibits the body of the carriage, the wheels and tracks not being shown.

20 B, C, D', are the window openings of the side.

25 On the top of the roof α of the car is placed a box or case E, which has a passage or pipe, D, leading out of its bottom, and into the interior of the car body. Within the case, E, are two cisterns or reservoirs F, G, between which there is a space, I, communicating with the pipe, D. A flap or board, G', is arranged across the middle of the case, E, and hinged to the upper part of it, as seen at α^2 , so that it may be moved freely in such manner as that its lower edge may be made to rest in contact with either 30 of the two adjacent sides b , c , of the two cisterns F, G. Within each cistern and extending from it to the top of the case E, I arrange three or any other suitable number of rows of vertical partitions or boards d , d , d , &c., e , e , &c., f , f , f , &c. These rows are placed at suitable distances apart, and the boards of one row are disposed so that they shall be at least equal in width to and opposite to the spaces between those of the 35 next row as seen in Fig. 5. These boards or partitions are composed in part or in whole of or are covered with sponge, or some other proper capillary attracting material, such as when the lower ends of the boards are 40 dipped in water placed in the cistern will attract or soak up the water and always keep

wet while there may be water in their cisterns:

45 Between each set of their partitions in each cistern and the outer end of each cistern, there is a vertical partition or wall, h , that is made to extend somewhat above the top of the case E, and to have arranged with respect to it, as seen in Fig. 2, an extension of the case, E, and a trumpet mouth or opening, i , leading into the said extension. The rear part of the extension is provided with one or more openings, k , k , to each of which a deflector plate, l , is applied as seen in the drawings. There is also an opening m , leading 50 out of the top of the case, E, and near to the partition h . For convenience of cleansing the reservoirs I make a portion or portions of the upper part or top of the case, E, to turn up or down on hinges as seen at 55 o , o , Fig. 2.

50 Each of the partitions, h , is calculated to extend down in the case E, to a short distance from the level of the water in its cistern, which level may be supposed to be 80 at the top of a cross partition, p , which may or may not be placed under the other partition, its object being to preserve the width of the opening or space, q , for the passage of the air under the partition, h , and to present 85 an impediment to the passage of large sparks or cinders, into that part of the chamber, E, which is between the deflector flap, G' , and the said partition, h .

55 When the car is running on the railway 90 so as to carry either of the trumpet mouths against the wind, whereby the wind may be caused to enter such mouth, such wind will pass from said case E, down the pipe D, and into the car. Such air in passing 95 through the case, E, will circulate against and between the capillary partitions and over the surface of the water in the cistern containing such partition. The sparks, dust, or cinders that may be floating in the induced current of air, will by infringement 100 against the capillary partitions be arrested and caught on them. The air will pass between the capillary partitions and deposit on them its dust and cinders, and thence enter into the middle part of the case, E, and strike against the hinged flap, G' , and pass down into the car. Should there be any smoke or light gases in the air after it has 105 passed under the partition, h , and into the middle of the case, E, such will find vent through or pass out of the opening m . In 110

which ever direction the cars may be moving, there will be a trumpet mouth open to receive the air and convey it into the car, it being robbed of its impurities by the purifying apparatus as described. This air after passing into the car is calculated to exert a pressure outward toward the windows, and in other directions, and by rushing out of the window openings it prevents currents 10 of air from flowing into them.

Above and below the range of window openings B, C, D'. I arrange two horizontal boards or troughs K, K, and between them and on the sides of each window, I 15 employ a series of turning blinds, or deflectors M, M, M, &c. Each of these blinds operates in connection with a vertical recess or chamber N, arranged in the side of each window opening and between the window 20 openings as seen in the drawings. Each of the said blinds is so made to turn on pivots or journals (as seen at y, y,) arranged at top and bottom of it, as that it may not only when inclined in one direction, rest at its 25 inner edge against one of the vertical sides of the recess, N, but when inclined in the opposite direction such inner edge may rest against the other vertical side of the recess n. Such positions of the blinds are de- 30 noted in Fig. 3, where they (the blinds) are shown by the black lines as standing in one direction, and by the red lines as standing in the opposite direction.

Each recess N, is to be provided with 35 one or more passages, r, r, made from it into the car. When the window openings are closed, these passages, r, r, not only serve to ventilate the car, but when the car is in motion, currents of air will be produced 40 through them, and caused by the inclined

blind to take such directions as will aid in preventing steam and dust from being blown against the glass of the windows. One or more of such recesses and hinged blinds may be applied to the bottom of the car as seen 45 in Fig. 2, wherein the recess is shown at O, and the turning blind at P. From the recess one or more openings, Q, lead into the car.

The turning blind M is so suspended, that 50 when the car is still, such blind will hang in a vertical plane, and when the car is in motion in the direction of the arrow, a', it (the blind) will stand as denoted by the black lines, as also when the car is in motion, in the direction of the arrow, b', the blind will take the position the reverse of that denoted by the black lines. This disposition of the blind and recess serves to 55 ventilate all that part of the car which is below the windows or near the floor, and takes off much of the dust that would rise from the floor.

What I claim as of my invention, is as 60 follows:

I claim two or more ranges of sponges or capillary partitions as arranged and combined with the cistern of water and open mouthed case, E, made to communicate with the interior of the car and the surrounding 70 atmosphere and to operate when the car is in movement substantially as specified.

In testimony whereof, I have hereto set my signature this eleventh day of March, A. D. 1853.

GEO. NEILSON.
